METHOD OF TREATING ARTICLES BEING GALVANIZED

Filed Dec. 23, 1925

Inventor
Theodore A. Dissel
Assignee Brown Company May
1925

UNITED STATES PATENT OFFICE.

THEODORE A. DISSEL, OF WINCHESTER, MASSACHUSETTS, ASSIGNOR TO CAMERON APPLIANCE COMPANY, OF EVERETT, MASSACHUSETTS, A CORPORATION OF MASSACHUSETTS.

METHOD OF TREATING ARTICLES BEING GALVANIZED.

Application filed December 23, 1925. Serial No. 77,260.

When small articles are to be hot galvanized they are first suitably "pickled" and it is then common practice to place them in a wire or perforated sheet metal basket which is dipped in molten zinc. The basket is then removed from the zinc and thoroughly shaken or placed in a centrifugal machine where it is rotated rapidly, either action causing most of the excess zinc to be removed from the articles. Either of these actions, however, is insufficient in many instances to produce a uniformly smooth coating on the articles and it has therefore been the practice to throw on to the hot articles while they are being shaken or after they have been centrifuged, a flux, such as sal ammoniac, zinc ammonium chloride, boric acid, etc. While this acts to improve the smoothness of the coating, it is often not entirely satisfactory, because many of the articles or portions thereof are often out of reach of the sal ammoniac or other flux which is thus ineffective to act upon them.

This invention provides a method and apparatus by which the flux is caused to act on all the articles and all portions of each, so that uniform, smooth, galvanizing throughout is effected. This is accomplished by vaporizing the flux and passing the vapors through the basket, preferably by operatively associating with and below the basket a hot plate on which the flux may be thrown in such manner that it is vaporized and the vapor passes up and through the basket and reaches all parts of each of the coated articles.

Preferably means are provided for enclosing the basket so as to cause substantially all of the fumes or vapors to pass therethrough before escaping.

For a more complete understanding of this invention, reference may be had to the accompanying drawings in which

Figure 1 is a top plan view of an apparatus designed to carry out the method of this invention.

Figure 2 is a section on line 2—2 of Figure 1.

Figure 3 is a detail section on line 3—3 of Figure 2.

Referring to these drawings, 1 indicates

the side wall of a casing having a removable cover 2 preferably hinged as shown at 3 in Figure 3, and formed when in closed position to make a substantially tight fit 55 with the upper edges of the side wall 1. This casing is provided with an elevated base plate 4 beneath which is positioned a suitable heating element 5, herein shown as a gas burner. Within the casing is positioned vertically a tubular member 6 designed to receive therein a basket 7 for containing the articles being galvanized. The upper end of the tubular member 6 is preferably flared outwardly as at 8 to facilitate 60 the placing of the basket therein, and the basket, according to the usual construction, is provided with oppositely disposed loops 10 through which may be passed hooks 11 attached to a lifting bar 12. At diametrically opposite points the wall portion 1 may be provided with slots as 111 to receive the bar 12 so that the basket may be suspended within the tubular member 6. This tubular member, as shown, is supported 75 within the casing by means of braces such as 15 and at its lower end there is preferably communicating therewith the upper end of a frusto conical baffle plate 16, the larger end thereof resting on the base plate 80 4. At 17 is shown a passageway leading from without the container through an opening 18 normally closed by means of a suitable shutter 19 through the baffle 16 so that through this passage the flux may be 85 inserted into the casing and deposited on the hot base plate 4.

The basket 7 may be of the type ordinarily employed for galvanizing in which the articles are placed in mass before being 90 dipped in the molten zinc after having been "pickled." On removal from the zinc bath the basket with its contents is either shaken thoroughly or placed in a centrifugal machine and rotated at a rapid rate, throwing 95 off most of the excess zinc from the articles. On removal from the centrifugal machine or after being thoroughly shaken and while the articles are still very hot, the basket with its contents is placed in the casing within 100 the tubular member 6 and the cover 2 is closed. The flux is then inserted through

- the passage 17 as by means of a shovel and thrown or scattered on the hot plate 4, whereupon it is immediately vaporized and the vapors pass upwardly through the basket 5 coming into contact with all portions of the articles therein, and escape through the exhaust pipe 20 which communicates with an opening through the casing above the basket. In some cases it may be found desirable to 10 shake or otherwise agitate the articles while they are being subjected to the vapor treatment, particularly where the articles, such as washers, have a tendency to pack closely together, the agitation aiding by permitting 15 the vapors to reach all parts of each article. After this treatment the basket with its contents is removed from the casing and the articles thereafter treated in the usual manner.
- 20 While one form of apparatus capable of being used for carrying out this process has been disclosed, it will be evident to those skilled in the art that various constructions may be used for this purpose and that many 25 modifications and changes may be made therein without departing from the spirit or scope of this invention as defined by the appended claims.
- 20 I claim:
- 30 1. Those steps in the process of galvanizing articles which comprise vaporizing a

flux, and passing the vapor through a mass of the hot zinc coated articles.

2. Those steps in the process of galvanizing articles which comprise dipping the articles in melted zinc, removing the greater part of the excess zinc, vaporizing a flux, and passing the vapors through a mass of the zinc coated articles while they are still hot from the dipping operation. 35

3. The method of galvanizing articles which comprises dipping the articles in melted zinc, centrifuging the articles, and passing vapors of a flux through a mass of the centrifuged articles while they are still hot 40 45 from the dipping operation.

4. That step in the process of galvanizing articles which comprises passing a vaporized flux through a mass of the hot zinc coated articles. 50

5. The steps in the method of galvanizing articles which comprises subjecting a mass of the hot zinc coated articles to a vaporized flux while agitating said mass.

6. The steps in galvanizing articles which 55 comprise enclosing the hot zinc coated articles, and subjecting the articles while so enclosed to a vaporized flux.

In testimony whereof I have affixed my signature.

THEODORE A. DISSEL.
